UNITED STATES PATENT OFFICE.

CHARLES W. NYE, OF MINNEAPOLIS, MINNESOTA, ASSIGNOR TO THE MINNESOTA STOVE COMPANY, A CORPORATION OF MINNESOTA.

RANGE.

1,309,099.

Specification of Letters Patent.

Patented July 8, 1919.

Application filed April 19, 1918. Serial No. 229,513.

To all whom it may concern:

Be it known that I, CHARLES W. NYE, a citizen of the United States, residing at Minneapolis, in the county of Hennepin and 5 State of Minnesota, have invented certain new and useful Improvements in Ranges, of which the following is a specification.

My invention relates to ranges, stoves and similar heating devices and has for its object in particular to provide a corner structure for porcelain ranges which will be attractive in appearance and at the same time strong and durable. A further object is to provide a structure of this kind which can 15 be readily assembled.

The full objects and advantages of my invention will appear in connection with the detailed description thereof and are particularly pointed out in the claims.

20 In the drawings, illustrating the application of my invention in a preferred form, Figure 1 is a side view of a portion of a range provided with my invention. Fig. 2 is a view in section on line 2—2 of Fig. 1. 25 Fig. 3 is a view in section on line 3—3 of Fig. 1. Fig. 4 is a plan view as seen inside the corner structure.

In the drawings, 10 designates a portion of the body of a range, the walls of which 30 have their corners or margins secured in a manner now to be described. 12 and 14 designate two of the plates or sheets constituting the walls of the range which are located at right angles to each other. These 35 plates are constructed of sheet metal, preferably of rolled sheet iron, coated with porcelain enamel. The plates near their ends are bent at right angles to form the portions 16 and 18 at the corners of the range 40 and a number of holes extend through the corner at 45 degrees thereto for receiving the bolts by which the plates are secured together. When the parts are assembled the plates are placed together with the portion 45 18 lying inside the portion 16 and a right angled strip 20 is placed on the outside to complete the joint. This right angled strip is preferably of nickel plated iron. It is provided with holes registering with the 50 holes in the plates which constitute the wall, and the corner edge is beveled at 22. Through the holes are passed bolts 24 having notched heads 26 fitting upon the beveled portion 22 and having the inner thread-

ed ends provided with nuts 28 which engage the plate 14 and the inner right angled portion 18. When the notched heads of the bolts are turned by a suitable tool the angular position of the nuts 28 will cause them to be held securely in place and prevented from turning.

The advantages of my invention will be obvious from the foregoing description. The provision of an outer strip of nickel plated metal not only gives a pleasing finish 65 to the corners but on account of the right angled shape thereof combined with the right angled ends of the two plates results in a very strong and durable corner construction. This is especially the case on account of the forty-five degree position of the securing bolts, while by placing the nuts for the latter inside the corner they are securely held in place and prevented from turning.

I claim:

1. A range comprising vertical end and side plates having their ends bent to form over-lapping right angled portions at the corners of the range, a right angled strip adapted to fit against the outer surface of 70 said corners, bolts passing through registering holes in the corners of the plates and the strip, and bisecting the right angled corners, said bolts having their heads fitting upon the outer surface of said strip, and 75 nuts on the other ends of said bolts fitting between the sides of the right angled corner.

2. A range comprising vertical end and side plates having their ends bent to form over-lapping right angled portions at the 80 corners of the range, a right angled strip adapted to fit against the outer surface of said corners, said strip having its outer edge beveled at forty-five degrees, bolts passing through registering holes in the corners of the plates and the strip and bisecting the right angled corners, said bolts having their heads fitting upon the beveled portion of 85 said strip, and nuts on the other ends of said bolts fitting between the sides of the 90 right angled corner.

3. A range comprising vertical end and side plates of porcelain enamel coated metal, each of said plates having its end formed with a right angled portion to overlap a corresponding right angled portion of the adjacent plate whereby the corners are of double thickness, a right angled nickel plated

metal strip adapted to fit upon the outer surface of said corners, said strip having its outer edge beveled at 45 degrees, bolts passing through registering holes in the corners 5 of the plate and the strip and bisecting the right angles, said bolts having their heads fitting upon the beveled portion of said strip

and nuts on the inner ends of said bolts fitting between the sides of the right angled corner.

10

In testimony whereof I hereunto affix my signature.

CHARLES W. NYE.
